(57) **CLAIM**

The ornamental design for a door latch assembly, as shown and described.

DESCRIPTION

FIG. 1 is a perspective view, taken from the front, top, and right side, of a door latch assembly, in accordance with our new design;

FIG. 2 is a front elevational view of the door latch assembly shown in FIG. 1;

FIG. 3 is a rear elevational view of the door latch assembly shown in FIG. 1;

FIG. 4 is a top plan view of the door latch assembly shown in FIG. 1;

FIG. 5 is a bottom plan view of the door latch assembly shown in FIG. 1;

FIG. 6 is a left side elevational view of the door latch assembly shown in FIG. 1; and,

FIG. 7 is a right side elevational view of the door latch assembly shown in FIG. 1.

The broken lines illustrate environmental structure which forms no part of the claimed design.
